UNITED STATES PATENT OFFICE

JOHN T. AUSTIN, OF HARTFORD, CONNECTICUT, ASSIGNOR TO THE AUSTIN ORGAN COMPANY, OF HARTFORD, CONNECTICUT, A CORPORATION OF CONNECTICUT

SWELL-SHUTTER-CONTROLLING MECHANISM

Application filed February 6, 1925. Serial No. 7,295.

This invention relates to swell shutter controlling mechanism for automatic organs, such as pipe organs, and has as its object to provide an improved arrangement wherein 5 the swell shutter means may be automatically controlled by a perforated music sheet to effect the desired increases and diminutions in the volume of tonal sounds of the pipes enclosed within the swell box.

10 In accordance with the present invention, I provide a plurality of instrumentalities adapted to operate, singly and in various combinations, upon the shutter or shutters to move the same to various predetermined positions, and a music sheet having perforations adapted, when passing over the tracker bar to control said instrumentalities singly and in the desired combinations. By practicing the present invention, a relatively large number 20 of different positions of the shutters, and, therefore, different degrees of volume of the sounds issuing from the swell box, may be obtained; the changes in the volume of sound may be brought about at various rates 25 of speed, and the ports in the tracker bar through which the instrumentalities are governed may be relatively few in number.

In the accompanying drawings I have shown, more or less diagrammatically, one 30 embodiment which the present invention may take, it being obvious that this disclosure is by way of exemplification only and that the structure is susceptible of various modifications and changes which would be within 35 the spirit of the invention without departing from the scope of the appended claims. For example, in the drawing the instrumentalities for operating the shutters are disclosed as bellows arranged in compound relation, 40 but, if desired, the operating means may be in part electric and in part pneumatic, and, if preferred, each of the pneumatics illustrated may be controlled through an individual primary bellows. Various other arrangements may be adopted.

In said drawings:

Figures 1 and 2 show diagrammatic organizations with the shutters in closed and 50 partly open positions, respectively; and

Figure 3 is a detail view taken substantially on line 3—3 of Fig. 1.

Referring to the drawing in detail, 10 designates a tracker bar having the usual holes 11 associated with the note playing mechanism, 55 and 12 is a note sheet adapted to pass over the tracker bar from one roll 13 to the other one and having note playing perforations 14 adapted to register with the holes 11. The swell box, designated by the numeral 15, 60 has an opening 16 in which is mounted the means for varying the volume of the sound and which means may be in the form of a pivoted shutter, or a plurality of shutters 17 connected by a rod 18.

In the present illustrative disclosure, the 65 shutter means is normally urged into open position by a tension spring 19 connected to the upper end of the rod 18, and the closing of the shutters against the tension of the 70 spring is effected through operating mechanism comprising a plurality of instrumentalities which are here shown as being in the form of bellows or pneumatics A, B, and C, mounted one on top of the other and varying 75 from one another in the amount to which they may be extended. By way of example, the bellows A is shown as having a single fold; the intermediate bellows B as having two folds, and the bellows C as having four 80 folds. The bellows B may be assumed as being capable of being extended twice as far as the bellows A, and the bellows C twice that of bellows B. The bellows may be associated with the shutters in any desired manner 85 to effect the proper operation of the shutters but, by way of exemplification, the shutters are shown as connected directly to the bellows by a link 20. It is understood that the spring may be employed to normally urge 90 the shutters into closed position, and the pneumatics may be employed for opening the shutters.

The pressures within the several pneumatics are controlled by the note sheet 12 as 95 it passes over the tracker bar, and to this end the several pneumatics A, B, and C, are respectively connected by tubes 22^a, 22^b, and 22^c, with ports 23^a, 23^b, and 23^c, in and adjacent, one end of the tracker bar, and the 100

note sheet has three lines of perforations 24^a, 24^b, and 24^c, adapted to respectively register with the ports 23^a, 23^b, and 23^c. Each of the pneumatics A, B, and C, is connected to an exhaust mechanism in such manner that when the port in the tracker bar associated with a given pneumatic is closed, that pneumatic will be collapsed and, when that port is opened or uncovered, the pressure within the given pneumatic will be raised to that of the atmosphere. For instance, the tubes 22^a, 22^b, and 22^c, may pass through an exhaust chamber 26, and the tubes may respectively have bleed openings 27^a, 27^b, 15 and 27^c. The bleed openings are smaller than the openings through the tubes so that a range in pressure within the several pneumatics, from substantially atmospheric pressure to the pressure obtaining within the exhaust chamber, may be obtained.

The operation of the arrangement described is briefly as follows: It will be understood that the perforations in the rows 24^a, 24^b, and 24^c, of the music sheet will be so arranged that the sheet will uncover and cover the ports 23^a, 23^b, 23^c, singly or in any desired combination depending upon the required volume of the sound. When the port 23^a only is uncovered, the pneumatic A alone will be extended, so that the shutters will be but slightly opened and a soft tone will be obtained. This condition prevails when the perforation 24^a registers with the port 23^a. When the port 23^b only is uncovered, the bellows B alone will be extended, so that the shutters will be opened to a slightly greater extent. This condition prevails when the perforation 24^b uncovers the port 23^b. The next position of the shutters is obtained by uncovering, at the same time, both of the ports 23^a and 23^b, which would be the case when the perforations 23^{a''} and 24^{b''}, respectively, register with the ports 23^a and 23^b, as shown in Fig. 2. When the port 23^c alone is uncovered, then the pneumatic C only will be extended, bringing the shutters to the fourth position. This will take place when the perforation 24^c registers with the port 23^c. The shutters are caused to assume the fifth position by extending both of the pneumatics A and B which would take place when the perforations 24^{a'''} and 24^{b'''}, respectively, register with the ports 23^a and 23^b. When the ports 24^{b'''} and 24^{c'''}, respectively, register with the ports 23^b and 23^c, the pneumatics B and C will be extended. The shutters will be opened to the fullest extent when the perforations 24^{a''''}, 24^{b''''}, and 24^{c''''}, respectively, register with the ports 23^a, 23^b, and 23^c, in which case, all of the pneumatics would be extended. It will be noted that the pneumatics may be so controlled by the note sheet, that one or more of the pneumatics may

be collapsing while another pneumatic, or other pneumatics are being inflated so that differential movements of the shutters may be obtained. It is, of course, understood that the arrangement of the perforations in the note sheet is diagrammatically shown solely for the purpose of making the description more clear.

From the foregoing description, taken in connection with the accompanying drawing, it will be clear that, by proceeding in accordance with the present invention, the shutters may be moved to a relatively large number of different positions so that the desired expression may be obtained. There are relatively fewer shutter controlling ports in the tracker bar than the number of positions which the shutters may be caused to assume, and this is of advantage as the ports require but very little space on the tracker bar and the width of the space taken up by the controlling perforations on the note sheet is relatively narrow.

What I claim is:—

1. In combination, a swell box having shutter means, operating means for moving the same to a plurality of open positions and including a plurality of instrumentalities each varying from one another in the extent to which they respectively move said shutters, and a tracker bar provided with a plurality of ports respectively associated with said instrumentalities and adapted to be controlled by a perforated note sheet passing over the tracker bar.

2. In combination, a swell box provided with shutter means, operating means for moving the same to a plurality of open positions and including a plurality of instrumentalities arranged to operate singly or in combination and each varying from the other in the extent to which they respectively move said shutter means, and a tracker bar provided with a plurality of ports respectively associated with said instrumentalities.

3. In combination, a swell box provided with shutter means, operating means therefor including a plurality of instrumentalities associated to operate singly and in selected combinations, a tracker bar provided with a plurality of ports respectively associated with said instrumentalities, and a note sheet passing over said tracker bar and having rows of perforations, one row for each port.

4. In combination, a swell box provided with shutter means, operating means therefor including a plurality of extensible bellows varying from one another in the extent to which they respectively move said shutter means, and a tracker bar provided with a plurality of ports respectively associated with said bellows.

5. In combination, a swell box provided with shutter means, a plurality of bellows in

compound relation, a tracker bar having a plurality of ports, one for each bellows, and a music sheet passing over said tracker bar and having rows of perforations controlling said ports.

- 5 6. In combination, a swell box provided with shutter means, a plurality of bellows operatively connected thereto and arranged to singly and severally expand and collapse
10 10 in various combinations, a tracker bar having a plurality of ports through which said bellows are controlled, and a music sheet passing over said tracker bar and controlling said ports.
- 15 7. In combination, a swell box provided with shutter means, a plurality of bellows in compound relation and operatively connected to said shutter means, said bellows varying from one another in the extent to
20 20 which they respectively move said shutters, a tracker bar provided with a plurality of ports corresponding in number to said bellows and respectively associated therewith, an exhaust chamber and a bleed opening leading from each bellows to said chamber, said bleed openings being relatively smaller than said ports.
